INTERNAL-COMBUSTION ENGINE

Harry E. Reiter, Sandusky, Ohio

Substituted for abandoned application Serial No. 373,356, January 6, 1941. This application June 28, 1944, Serial No. 542,501

2 Claims. (Cl. 123—18)

This invention relates to internal combustion engines and particularly to the type wherein the motion of oscillating pistons is converted into rotary motion of a drive shaft. This application is a substitute for my application Serial No. 373,356, filed January 6, 1941.

Internal combustion engines of this general type are well known and have not proven commercially feasible due possibly to certain inherent faults of design. This is particularly true with respect to the specific mechanism normally provided for converting the oscillating motion of the pistons into rotary motion of the drive shaft.

In some instances, combustion engines of this general type omit entirely any mechanism for converting the oscillating motions of the pistons into rotary motion of the drive shaft, and merely provide an external oscillating drive or crankshaft to which the necessary mechanical connections must then be made. In other instances, the oscillating motion of the pistons is converted to rotary motion by various means external of the engine casing, such as pitmans connected to oscillating cranks and thence to other cranks, etc. It is obvious that in any of the above cases not only is considerable power lost through friction of the additional parts but more important, additional stresses and torsional forces are set up requiring stronger and heavier parts and resulting generally, in larger and bulkier machines per rated horsepower in which the maintenance requirements are considerably greater.

It is accordingly, the chief object of this invention to provide an efficient, compact engine structure which is completely self-contained and which will convert the power generated on the heads of the oscillating pistons to rotary motion of a driving or crankshaft without the disadvantages hereinbefore set forth.

A further object is to provide an internal combustion engine which will convert the oscillating motion of the pistons into a rotary motion of the drive or crankshaft by means of only these two moving parts.

A further object is to provide an internal combustion engine of the type described wherein the component parts are so arranged as to eliminate excessive strains or torsional forces thereon.

A further object is to provide an internal combustion engine wherein an oscillating piston unit is directly connected by a sliding or rolling bearing to a crank pin so as to produce rotary motion of the crankshaft.

A further object is to provide an internal com-

bustion engine of the type described in which the means for converting the oscillating motion of the pistons to rotary motion of the driving or crankshaft lies in the same general plane as the pistons.

A further object is to provide a strong, compact and completely self-contained power unit consisting of a plurality of pistons and a single throw crankshaft directly connected by a single bearing, thus eliminating connecting rods, pitmans, etc.

A further object is to provide novel means for maintaining high compression in the combustion chambers by a novel arrangement and assembly of the parts thereof.

A further object is the provision of novel packing means for the arcuate pistons to ensure a gas-tight seal between the four sides of the piston and the cylinder and its side-walls.

A further object is the provision of an internal combustion engine of the type described wherein the number and arrangement of the component parts are reduced and simplified whereby construction of the apparatus as a whole results in material reduction in initial cost, operation cost, and cost of maintenance and repair.

Other objects and advantages of the invention will become apparent during the course of the following description.

20 In the drawings I have disclosed one embodiment of the invention. In this showing:

Figure 1 is a front elevation of the invention, Figure 2 is a rear elevation thereof,

Figure 3 is a central vertical section taken perpendicular to the axis of oscillation of the engine,

Figure 4 is a section taken on line 4—4 of Figure 1,

Figure 5 is a section taken on line 5—5 of Figure 1,

Figure 6 is a perspective view of the rocker unit showing one of the pistons mounted thereon,

Figure 7 is a perspective view of the crankshaft, and

Figure 8 is a perspective view of a packing for the pistons.

Referring to the drawings it will be noted that the engine comprising the present invention is formed of five main parts, namely, a cylinder block 10, a front head 11, a rear head 12, a rocker assembly 13 and a counterbalanced crank shaft 14. As will become apparent, the rocker and crank shaft cooperate with each other to convert oscillating movement of the rocker unit into rotary movement of the crank shaft. It also will become apparent that of the five main component

parts of the engine, only two are movable, namely, the rocker unit and crank shaft, thus providing an extremely simplified and compact power unit which, due to the arrangement of the parts as will be described, eliminates the difficulties of design and transmission of generated power usually encountered in internal combustion engines of this general type.

Referring to Figure 3 it will be noted that the cylinder block comprises inner and outer cylindrical walls 15 and 16 respectively and these walls are concentric to each other. The outer wall 15 is shown as being provided with an internal base 16' for securing the engine to a suitable support. While an engine of the stationary type has been illustrated, it will be obvious that the engine is capable of any use to which an internal combustion engine can be put. The cylinder block is provided at diametrically opposite points with integral connecting webs 17 and 18 between the inner and outer walls 15 and 16 to define two substantially semi-circular chambers 19 and 20 to receive the pistons to be described.

In the embodiment of the invention illustrated firing occurs in the upper part of the engine, as will be described, and to assist in dissipating heat, the block 10 is provided with radiating fins 21 while the front and rear walls 11 and 12 are provided with similar fins 22. For a reason to be described, the inner wall 16 is provided with diametrically opposite openings 24, and between these openings an arcuate web 25 extends, this web being cast integral with the wall 16 and forming with the upper portion of such wall a space 26 for the passage of air through the engine. The portion of the wall 16 defining the top of the space 26 is also provided with radiating fins 27. The front and rear walls 11 and 12 are bolted to and against opposite faces of the block 10 by suitable bolts 28 to form, in effect, an integral casing unit. The contacting faces of the elements of this unit are ground and lapped to provide a leak-proof joint for a reason which will become apparent.

The rocker 13 comprises a central substantially arcuate body 29 having diametrically oppositely projecting arms 30 for a purpose to be described. The body of the rocker is provided with aligned supporting shafts 31 (Figures 4 and 6) arranged axially of the cylinder block and supported in bearings 32 mounted in aligned cylindrical extensions 33 formed integral with the respective front and rear plates 11 and 12. Axially through the shafts 31 are respectively drilled passages 34 and 35 (Figure 4) and these passages are offset from each other to communicate with upper and lower passages 36 and 37 drilled parallel to each other through the body 29 and arms 30. The passages 34 and 35 communicate respectively with inlet and outlet fittings 38 and 39 connected to a suitable heat exchanger for the circulation of water through the engine in a manner to be described. The fittings 38 and 39 have their inner ends formed as packing glands slideable on the ends of the cylindrical extensions 33 and provided with the usual packing as shown in Figure 4. Each fitting is connected to the adjacent plate 11 or 12 by bolts 38' which may be taken up to compress packing in the fittings. The radially outer ends of the passages 36 and 37 communicate with each other as at 40 (Figure 3) but the end portions of the passages 36 are blocked off as at 41 to prevent the passage of water radially outwardly through the passage 36 and thence downwardly through the connections 40. Each con-

nection 40 has an inlet port 42 while a similar port 43 is provided for each end of the passage 36.

The crank shaft 14 is arranged below and parallel to the axis of the rocker unit and is journaled in bearings 44 mounted in cylindrical extensions 45 formed integral with the respective plates 11 and 12. The crank shaft is shown in the present instance as a single throw shaft and the single crank 46 of the shaft is rotatable in a bearing block 47 reciprocable in a radial slot 48 formed in the bottom portion of the body 29 of the rocker. It will be apparent that this connection between the rocker and the crank 46 provides means for translating the rocking movement of the rocker 13 into rotary movement of the crank shaft. The crank shaft is suitably counterbalanced as at 49 (Figures 4 and 6) and one end of the shaft may be notched as at 50 to provide suitable means for operating a timer (not shown).

Pistons 51 and 52 are mounted in the respective chambers 19 and 20 and oscillate in such chambers. It will be apparent that the pistons are arcuate in contour and correspond in cross-sectional shape to the cross-sectional shapes of the chambers in which they are arranged. The piston 51 divides the semi-circular chamber 19 into a compression chamber 53 and firing chamber 54, while the piston 52 similarly divides the semi-circular chamber 20 into a compression chamber 55 and firing chamber 56. Each of the two piston structures is mounted on one of the projecting arms 30 of the rocker structure as shown in Figures 3 and 6.

The upper end of each piston is provided with an inner wall 57 spaced from the outer wall of the piston to provide a water space 58. The radially outer portion of each space 58 communicates with one of the openings 42 (Figure 3) while the radially inner portion of each space 58 communicates with one of the ports 43. Accordingly it will be apparent that water flowing through passages 36 will flow through the circulating space 58 of each piston, through ports 43 and thence from port 42 of each piston to be returned to the source through passages 37 and 35.

The two face plates 11 and 12 are lapped and ground to provide an accurate fit against the sides of the piston while the radially inner and outer surfaces of the pistons are accurately fitted to the corresponding walls of the block 10. In practice therefore, it has been found that a substantially leak-proof contact is provided between the pistons and cylinders. However, to further provide against leakage of pressure and possible oil pumping, the pistons may be provided with the novel sectional packing rings as shown in Figure 8, each ring being designated as a whole by the numeral 60. If desired, the end of each piston adjacent its combustion chamber may be provided with three rings while the compression end of each piston may be provided with two rings, although it will be obvious that any desired number of rings may be employed. Referring to Figure 8, it will be seen that each packing ring comprises four elements 61 which may be similarly constructed and in fact, if the pistons are square in cross-section, the packing elements 61 may be identical. Each packing element 61 is provided at one end with a notch 62 and at its other end with a projecting tongue 63 receivable in the notch 62 of the next adjacent packing element 61. These elements, when assembled, form a perfect square or other rectangle having an external shape identical with that of the piston with which

the packing unit is associated. Each packing element 61 is preferably backed up by a suitable leaf spring 61'.

The plate 11, in the two-cylinder embodiment of the invention shown, is provided with a pair of arcuate plates 64 having flanges 65 (Figures 1 and 5) projecting toward and seating against the plate 11. Each plate 64 is secured in position by certain of the clamping bolts 28. Each plate 64 therefore forms with the plate 11 an arcuate chamber 66 for the passage of the combustible mixture from the compression end of each cylinder to the combustion end thereof. Each chamber 66 has its lower end communicating with the adjacent compression chamber 53 or 55 through suitable ports 67 in the plate 11 to receive compressed fuel from the chamber 53 or 55. It will be noted that the ports 67 communicate with the compression chambers 53 and 55 adjacent the lower limits thereof so that the combustible mixture will be released from the compression chambers only at the approximate point of maximum compression. The fuel is admitted into the compression chambers 53 at a higher point, the plate 12 (Figure 2) being provided with admission ports 68 for the respective compression chambers 53 and 55. The relative locations of the ports 67 and 68 are apparent in Figure 1.

As shown in Figures 1 and 5 each passage or duct 66 communicates at its upper end through ports 69 with one of the combustion chambers 54 or 56, and it will be apparent that the ports 69 communicate with the respective combustion chambers when the pistons are adjacent the lower limits of their strokes, at which time the scavenging of the combustion chambers likewise takes place. In other words, the engine shown in the drawings is a two-stroke cycle engine, although it will be obvious that the structural characteristics and advantages of the construction readily may be embodied in engines of other types such as the four-stroke cycle or Diesel type engine. In order to prevent direct straight line communication across each combustion chamber between the intake openings 69 and the exhaust openings 70 (Figure 5) the upper end of each of the pistons may be provided with a sloping wall 71 to form a baffle surface 72.

As indicated above, each combustion chamber is provided with exhaust ports 70 which are opened by the respective pistons adjacent the lower limits of their strokes. As shown in Figures 2 and 5, the exhaust ports communicate with an exhaust manifold 71 flanged as at 72 for connection with a suitable exhaust pipe (not shown).

The wall 11 is provided with a pair of threaded openings 73 to receive ignition plugs 74 and the location of these plugs is shown in Figure 1 adjacent the upper and inner limits of the combustion chambers 54 and 56. The plugs 73 are controlled by any suitable type of ignition system and since the engine obviously may be used with any conventional type of ignition system, such system has not been illustrated. For a similar reason no carburetor or other charge forming device has been illustrated since it is obvious that any desired type of charge forming device or devices may be employed for supplying the combustible mixture to the engine through the ports 68.

The operation of the engine is as follows:

Rocking movement of the rocking unit 13 obviously alternately expands and contracts the compression chambers 53 and 55 upon the arcuate

reciprocation of the pistons. A suitable charge forming device, as previously stated, may be used to supply fuel through the ports 68 (Figures 1 and 2) into the chambers 53 and 55. Assuming that the rocker is turning in a counter-clockwise direction, the movement of the piston 51 will create a partial vacuum in the chamber 53. A partial vacuum will be created in the chamber 53 and the pressure in this chamber will continue to drop until the lower end of the piston 51 uncovers the adjacent port 68, at which time a fuel charge will rush into the chamber 53. When the oscillating movement of the rocker reverses, the pistons will start to turn in a clockwise direction and movement of the lower end of the piston across the corresponding port 68 will close this port and trap the fuel charge in the chamber 53. At this time it should be noted that the upper ports 69 (Figures 1 and 5) will be closed and accordingly counter-clockwise turning movement of the piston 51 will compress the charge in the chamber 53 and in the duct 66 (Figure 5). As soon as the upper end of the piston 51 uncovers the corresponding intake opening 69 compressed fuel will rush into the combustion chamber and this action takes place simultaneously with the exhausting of burned gas through the corresponding port 70 (Figures 2 and 5). The rush of unburned gas directly across the cylinder from the port 69 to the port 70 will be prevented by the baffle 72 (Figure 6) in accordance with conventional two-stroke cycle practice.

When the oscillating movement of the rocker again reverses and the rocker starts to turn in a counter-clockwise direction, the previously described operations will be repeated with respect to the compression chamber 53 while the fresh charge of fuel in the combustion chamber 54 will be compressed. Slightly ahead of the point at which the upper end of the piston 51 reaches its upper and inner limit of movement, the timer of the ignition system will cause the charge to be exploded to start to turn the rocker in a clockwise direction, the burned fuel again escaping through the exhaust port 70 of the combustion chamber 54 when the exhaust port is opened by the upper end of the piston 51, as explained above.

It will be obvious that all of the operations described with respect to the piston 51 likewise take place with respect to the piston 52 and need not be particularly described. The only difference between the function of the parts associated with the two pistons is that the functions of the two pistons take place alternately, the charge in the chamber 54 exploding and expanding while the piston 52 is moving upwardly to create a partial vacuum to induce the necessary flow of fuel into the chamber 55. Similarly, the fuel charge in the combustion chamber 56 explodes and expands simultaneously with the creation of a partial vacuum in the compression chamber 53 to induce the flow of fuel into such chamber.

It will be obvious that the oscillating movement of the rocker 13 takes place to the extent necessary to move the axis of the crank 46 laterally of the vertical center of the crank shaft a distance equal to the offsetting of the crank from the crank shaft. Accordingly the oscillating movement of the rocker is translated into rotary movement of the crank shaft.

The crank 46 and its connection with the rocker 13 and associated elements forms one of the important characteristics of the invention. The present construction not only completely eliminates the use of connecting rods but also arranges

the pistons and the motion translating means between the rocker and crank shaft in a common plane. Thus the elimination of means externally of the plane of the pistons for connecting the rocker to the crank shaft completely eliminates the objectionable torsional vibrations which are always present in such a mechanical arrangement. Moreover, the present construction minimizes the length of the motor, that is, the size of the motor in a direction parallel to the crank shaft.

The present construction lends itself readily to air cooling, both combustion chambers being completely surrounded by radiating fins as will be apparent from an examination of Figures 1, 3 and 4. However, more efficient cooling is provided by the water circulating system shown. Water or any other desired cooling medium may be supplied through the fitting 38 to the passage 34 from whence it flows in opposite directions as viewed in Figure 3 into the radially inner portion of each chamber 58 and thence out of the radially outer portion of this chamber through ports 42 into the ends of the passage 37. As will be apparent from Figure 4, the liquid from the passage 37 will flow through passage 35 to be discharged through the fitting 39 to a suitable heat exchanger (not shown).

It will be obvious, of course, that the slot 48 may be equal in width to the diameter of the crank 46 to directly transmit power thereto. The use of the bearing block 47, however, is greatly preferred since it eliminates lines of contact between the slot 40 and crank 46 and provides broad and adequate bearing surfaces which greatly increases the length of the mechanical connection between the rocker and the crank. This arrangement, of course, directly transmits power to the crank shaft without the use of piston pins and connecting rods. The construction moreover, provides for a relatively long-stroke piston with a relatively short throw crank, thus resulting in a high piston speed with relation to crank shaft speed. Accordingly it is possible without increasing the size of the engine to provide a leverage between the rocker and crank shaft which is substantially greater than that usually employed in a reciprocating type engine.

As previously stated, the engine is shown as being of the two-stroke cycle type, but obviously may be adapted for four-stroke cycle use. In such case suitable conventional valves would be employed for the combustion chambers. Moreover, in such type of engine, the pistons may be double-acting, all of the chambers 53, 54, 55 and 56 becoming combustion chambers. The firing order of such a four-stroke cycle engine would be consecutive in one direction circumferentially around the engine, thus providing maximum power with minimum loss due to friction and accordingly providing smooth and efficient operation.

It will be obvious that the lower part of the interior of the inner wall 16 serves as the crank case of the engine, and accordingly the crank 46 and bearing block 47 constantly operate in a bath of oil to materially reduce friction and wear. The cylinder walls have no direct open communication with the crank case and accordingly there is no excess splashing of oil on the cylinder walls through which excessive oil pumping can occur. Three sides of each piston, that is, each side except the radially inwardly facing side, operate throughout their area against a wall of the cylinder or plates 11 or 12. The remaining or radially

inner face of each piston communicates with the space within the wall 16 to receive through the openings 24 sufficient oil to lubricate the pistons without providing excessive lubrication through which excessive carbonization of the combustion chambers and oil pumping can occur.

It will be obvious that the entire engine may be readily and easily assembled in much less time than is required with other internal combustion engine structures. Each piston is shrunk on its associated arm 30 and the entire rocker structure thereby becomes, in effect, a single unit. The rocker unit may be placed in position by inserting it axially into position. The openings 24 are cut through at least one side of the cylinder block to permit such insertion to take place. The two walls 11 and 12 are then placed in position against opposite sides of the cylinder block and bolted thereto. The mode of assembling the other elements of the structure such as the spark plugs, exhaust manifold, etc. will be obvious.

Accordingly it will be apparent that the present construction embodies only five main units, namely the cylinder block, the two side walls, the rocker and the crank shaft, thus providing for extreme simplicity in design and economy in manufacture. It also will be apparent that the device comprises only two main moving parts, namely, the rocker and the crank shaft, the simple bearing block 47 forming the only other movable element of the engine.

The compact design of the engine permits a wide range of use as to space requirements with respect to the power required. For example, the required power can be delivered by an engine of small over-all height and greater cross-section or by one of larger over-all height and smaller cross-section, depending also, of course, on the type of engine required. The engine accordingly is capable of flexibility in design and the space requirements for an engine of given power is less than that of a conventional engine.

The high piston speeds and comparatively low crank shaft speeds produce very high torque, thus greatly increasing the mechanical efficiency of the unit with a corresponding improvement in fuel consumption at both high and low speeds. The heavy pressures on cylinder and piston walls present in conventional engines, caused by thrusts incident to the angularity of the connecting rods with respect to the pistons, are absent in the present construction due to the elimination of the connecting rods. By eliminating conventional piston pins, the wear and lubrication problems incident to the use of these elements are eliminated.

In many installations, reduction gears in the final drive may be eliminated due to the design of the motor which permits very high piston speeds at comparatively low crank shaft speeds with increased torque on the crank shaft.

It is to be understood that the form of the invention herewith shown and described is to be taken as a preferred example of the same and that various changes in the shape, size and arrangement of parts may be resorted to without departing from the spirit of the invention or the scope of the subjoined claims.

I claim:

1. An internal combustion engine comprising a three-part casing including an integral cylinder block formed of inner and outer substantially cylindrical walls and circumferentially spaced integral webs connecting said walls, and front and rear heads secured against said block and coop-

erating with said walls and said webs to form an arcuate cylinder, said inner wall having a radial opening therethrough spaced from said webs, an arcuate piston mounted for movement in said cylinder, a rocker body within said inner wall and connected to said piston through said opening, a crank shaft parallel to the axis of said rocker, a crank on said shaft arranged in the plane of said cylinder block, and means arranged in said plane for imparting rotational movement to said shaft through said crank upon rocking movement of said rocker body.

2. An internal combustion engine comprising a three-part casing including an integral cylinder block formed of inner and outer substantially 15

5 cylindrical walls and circumferentially spaced integral webs connecting said walls, and front and rear heads secured against said block and cooperating with said walls and said webs to form an arcuate cylinder, said inner wall having a radial opening therethrough spaced from said webs, an arcuate piston mounted in said cylinder, a rocker body connected to said piston through said opening and arranged in the plane of said cylinder block, said rocker body being supported to rock on the axis of said cylinder, and a crank shaft having a crank thereon arranged in said plane, said rocker body having a radial slot receiving said crank.

HARRY E. REITER.
